UNITED STATES PATENT OFFICE.

AMANDO M. OJEDA, OF LOS ANGELES, CALIFORNIA.

TAMALE-MAKING APPARATUS.

Application filed February 1, 1922. Serial No. 533,289.

To all whom it may concern:

Be it known that I, AMANDO M. OJEDA, a citizen of Mexico, residing at Los Angeles, in the county of Los Angeles and State of California, have invented new and useful Improvements in Tamale-Making Apparatus, of which the following is a specification.

My invention relates to apparatus for making tamales, and a purpose of my invention is the provision of an apparatus of this character in which mechanism is provided for successively feeding corn husks to the discharge end of a magazine from which is forcibly fed the material of which a tamale is formed, and means associated with the magazine for spreading the material over the surface of the corn husks. Furthermore, my invention provides an apparatus which delivers the material and husk to a remote point for a subsequent folding of the husk in completing the making of the tamales.

I will describe one form of tamale making apparatus embodying my invention and will then point out the novel features thereof in claims.

In the accompanying drawings,

Figure 1 is a view showing in side elevation one form of tamale making apparatus embodying my invention.

Figure 2 is an end elevation of the apparatus shown in Figure 1.

Figure 3 is an enlarged view partly in vertical section of the magazine and adjacent mechanism.

Figure 4 is a vertical sectional view taken on the line 4—4 of Figure 3.

Figure 5 is an enlarged fragmentary view showing the magazine and husk feeding mechanism in front elevation.

Similar reference characters refer to similar parts in each of the several views.

Referring specifically to the drawings, my invention in its present embodiment comprises a table designated at T and including legs 15 for supporting the table top 16 in the desired horizontal plane. The legs are connected by a platform 17 upon which is sustained the actuating mechanism for the apparatus. At one end of the table top 16 vertical standards 18 are secured to the top and at the corners of a rectangle, the upper ends of these standards being slotted as indicated at 19 in Fig. 2 for the reception of bolts 20 carried by bars 21 secured to an annular bracket 22, it being understood that

the bolts are adjustable vertically within the slots 19 to vary the horizontal position of the bars 21 and consequently the bracket 22. Within the bracket 22, a magazine M is 60 adapted to be sustained, the latter in the present instance being of cylindrical form and having its upper end closed by a convex cover plate 23 detachably secured by means of pivoted securing members 24. 65

As shown in Figure 3, the lower end of the magazine M is formed with a tapered spout 25 through which the material forming the tamale is adapted to be discharged. The discharge of the material from the spout 25 can be regulated by means of a shutter 26 slidably fitted on the track 27 formed on the spout, and adjustable by means of a nut 27^a threadedly fitted on the bolt 28 riveted to the spout 25, and grooved to receive a pair of 75 ears 26^a formed on the shutter 26. In effecting a spreading of the material over the husks after its discharge from the spout 25, I provide a presser plate 29 formed with a forwardly curved lower end having a concave edge as clearly shown in Figure 5. The upper end of the plate 29 is slotted as indicated at 30 to receive a threaded stud 31 carrying a ring nut 32, the stud being mounted in the spout 25 and the ring nut 85 operating to clamp the plate in any vertically adjusted position.

As illustrated to advantage in Figures 3 and 5, a relatively large wheel W is fixed to a shaft 33 at such point as to be directly 90 below the discharge end of the spout 25. The periphery of the wheel W is formed with an annular convex portion 34 bordered by annular flat portions 35 all as clearly shown in Figure 4. Framed about the wheel W is 95 an endless belt B formed of canvas or other suitable material and also trained about a pulley P mounted on a shaft 36 positioned within that end of the table remote from the magazine M so that the periphery of the 100 pulley is disposed above the surface of the table top. Suitable openings are formed in the table top 16 to allow of the passage of the upper stretch of the belt B above the table top and forwardly in the direction of 105 the arrow in Figure 1.

For the purpose of maintaining the corn husks in proper position upon the belt B during the passage of the latter around the wheel W, gripping rollers R and endless 110 belts B' are provided and so arranged that the belts are maintained in contact with the

flat portions 35 of the wheel W, it of course being understood that the belt B and the corn husks are interposed between the wheel and the belts B', as clearly shown in Figure 4. The rollers are arranged in pairs, with the forward pair of rollers mounted on the confronting ends of shafts 37 journaled in bearings 38. The rear pair of rollers are mounted in a similar manner on shafts 39, 10 it being noted however that the shafts 39 are in a plane slightly above the shafts 37 so that the corresponding rollers occupy a similar position. This particular arrangement is for the purpose of maintaining the belts B' in 15 proper contact with the wheel W so that the picking up and discharging of the corn husks is rendered automatic, while at the same time permitting of the discharge of the dough onto the husks during the period in 20 which they are held firmly on the belt B.

To effect the discharge of the dough from the magazine M, a follower 39 is adapted to be superimposed upon the material as shown in Figure 3 and forced downwardly within 25 the magazine by compressed air introduced into the magazine through a pipe 40 mounted in the cover 23 and connected to a flexible pipe 41 which latter in turn communicates with an air pump 42. A check valve 43 is 30 arranged at the end of the pipe 41 and a relief valve 43^a is mounted in the cover 23 which is manually adjustable to allow the escape of air from the magazine to maintain a predetermined air pressure within the 35 magazine irrespective of the speed or dimensions of the pump.

The mechanism for actuating the pump 32 and the wheel W may be of any suitable form. However, in the present instance I 40 have shown a motor 44 mounted on the platform 17 and operatively connected to a shaft 45 through a pulley and belt connection. The shaft 45 in turn is operatively connected to the air pump 42 through a pulley and belt 45 connection, and to a shaft 46 through a similar connection. The shaft 46 is journaled in hangers 47 arranged so that the shaft is disposed at right angles to the shaft 33. The shaft 46 is operatively connected to the shaft 33 by a worm 48 fixed to the shaft 46 and meshing with a gear 49 fixed to the shaft 33.

The operation of the apparatus is as follows: The corn husks designated at H in Fig. 3 are adapted to be inserted between the 55 forward portions of the belts B and B', and with the wheel W moving in the direction of the arrow it will be clear that the husks are fed forwardly and upwardly to a point beneath the discharge end of the spout 25. As each husk is inserted between the belts, the forward rollers R co-operate with the 60 flat surfaces 35 of the wheel W in effectively gripping the end portions of the husks so that they are held substantially taut over 65 the convex portion 34 thus occupying the

position shown in Figure 4. The husks are held in this position prior and subsequent to the passing of the spout 35, and when reaching a point below the spout the dough material is discharged upon the husk. Practically simultaneously with this discharge operation, the presser plate 29 operates to press the dough so as to cause it to adhere to the surface of the husks so that the only further operation necessary to complete the 75 formation of the tamale is the folding of the husk to enclose the dough. The belt B functions to feed the husks with their dough forwardly over the table T which operators remove and perform the folding operations 80 in completing the tamales.

By virtue of the adjustment of the shutter 26 and the presser plate 29, it will be clear that the amount of material discharged upon each husk and the pressure with which it is 85 packed can be varied in forming tamales of different sizes. It is to be understood that a wheel having a flat periphery can be substituted for the wheel W when making tamales with a paper wrapping. 90

Although I have herein shown and described only one form of tamale making apparatus embodying my invention, it is to be understood that various changes and modifications may be made herein without departing from the spirit of the invention and the spirit and scope of the appended 95 claims.

What I claim is:

1. A tamale making apparatus comprising a constantly movable conveyor, gripping means for holding corn husks on said conveyor, means for discharging a tamale forming dough on the husks, and means for spreading the dough over the husks. 100

2. A tamale making apparatus comprising an endless conveyor belt, a dough containing magazine above the belt and having a spout for discharging the dough onto said belt, and means for holding corn husks on 105 said belt to receive said dough.

3. A tamale making apparatus comprising an endless conveyor belt, a dough containing magazine above the belt and having a spout for discharging the dough onto said belt, means for holding corn husks on said belt to receive said dough, and means for spreading the dough over said husks. 115

4. A tamale making apparatus comprising a wheel, an endless belt trained about 120 the wheel, gripping rollers positioned above the wheel, belts trained about the gripping rollers and contacting with the belt of said wheel for holding corn husks on said belt, and a dough containing magazine arranged above said wheel and having a discharge spout interposed between said rollers for discharging dough onto said corn husks. 125

5. A tamale making apparatus comprising a wheel, an endless belt trained about 130

- the wheel, gripping rollers positioned above the wheel, belts trained about the gripping rollers and contacting with the belt of said wheel for holding corn husks on said belt,
- 5 5 a dough containing magazine arranged above said wheel and having a discharge spout interposed between said rollers for discharging dough onto said corn husks, a shutter for controlling the discharge of
- 10 10 dough from said spout, and a spreading plate adjustably sustained on the spout for effecting a spreading of the dough over said husks.
6. A tamale making apparatus comprising a wheel, an endless belt trained about the wheel, gripping rollers positioned above the wheel, belts trained about the gripping rollers and contacting with the belt of said wheel for holding corn husks on said belt,
- 15 15 20 20 a dough containing magazine arranged above said wheel and having a discharge spout interposed between said rollers for discharging dough onto said corn husks, pneumatic means for effecting a discharge
- 25 25 30 30 of the dough from said spout, an adjustable shutter for controlling the discharge of dough, and a spreading plate adjustable on the spout for effecting a spreading of the dough over said husks.
7. A tamale making apparatus comprising a wheel having its periphery formed with an annular convex portion and annular flat portions bordering the convex portion, an endless belt trained about said wheel and flexible to conform to the contour of the periphery thereof, gripping rollers arranged
- 35 35 in pairs, endless belts trained about said rollers, the arrangement of said rollers being such that one stretch of said belts is in contact with those portions of the first belt
- 40 40 tact with those portions of the first belt

which engage the flat portions of said wheel, a magazine arranged above the wheel and having a discharge spout disposed between said pair of rollers, pneumatic means for forcibly ejecting dough from said spout, a 45 shutter adjustable to control the said spout, and a spreader plate adjustable on said spout for the purpose described.

8. A tamale making apparatus comprising a wheel having its periphery formed with an annular convex portion and annular flat portions bordering the convex portion, an endless belt trained about said wheel and flexible to conform to the contour of the periphery thereof, gripping rollers arranged in pairs, endless belts trained about said rollers, the arrangement of said rollers being such that one stretch of said belts is in contact with those portions of the first belt which engage the flat portions of said wheel, 50 a magazine arranged above the wheel and having a discharge spout disposed between said pair of rollers, a follower within said magazine, pneumatic means acting on said follower for ejecting dough from said magazine through said spout, a shutter adjustable to control said spout, and a spreader plate adjustable on said spout for the purpose described.

9. A tamale making apparatus comprising a constantly movable conveyor, gripping means for holding sheets of paper on said conveyor, means for discharging a tamale forming dough on the sheets of paper, and means for spreading the dough over the 75 sheets of paper.

In testimony whereof I have signed my name to this specification.

AMANDO M. OJEDA.
